UNITED STATES PATENT OFFICE.

HAROLD A. SAMPSON, OF BURLINGAME, CALIFORNIA.

GOLF-CLUB-CARRYING CASE.

Application filed March 2, 1925. Serial No. 12,711.

My invention relates to golf bags, and one of the objects of the invention is to provide a combination bag and case, so that a case is provided in which balls, clubs and special 5 or other clothing in addition to the clubs may be carried.

Referring to the drawings:—

Figure 1 is a side elevation of the carrying case, a portion being broken away to 10 disclose the structure.

Figure 2 is a perspective view of the carrying case having one side open to disclose the packing chamber. The dotted lines indicate the position of the cap which covers the 15 projecting ends of the clubs.

Figure 3 is a sectional view, the plane of section being indicated by the line 3—3 of Figure 1.

Figure 4 is a perspective view of the cap, 20 a portion being broken away to disclose the structure.

Figure 5 is a detail in perspective of one corner of the cap showing the projecting stud.

Broadly my invention comprises a combined carrying case and golf-bag which resembles a neat traveling case when closed. A central portion is provided to receive the golf clubs, and on opposite sides of this 25 central portion, carrying chambers are provided in which clothing or other articles may be placed. A collapsible cap is also provided to cover the exposed ends of the clubs when traveling, and this cap is secured from the inside of the case so that it cannot be removed without opening the case.

In detail my invention comprises a case in which is disposed a central portion 7, having a plurality of separate club compartments 8 and the larger compartments 9 30 each of which is adapted to receive an umbrella or a tube of balls. These compartments are preferably arranged in a column having overhanging bases 11 and 12. In other words, a cross section of the central portion 7 has the shape of a capital I.

One end of the case is closed by a suitable sheet 13, and the other end of the case is covered with a similar sheet 14, having apertures therein in register with the compartments 8 and 9, so that these compartments are open and the rest of the end is closed. The sheets 13 and 14 are preferably of the same height as the portion 7, but are extended laterally beyond the ends of the 50 overhanging bases 11 and 12 to give the

desired width to the case. A small aperture 16 is provided adjacent each corner of the plate 14 to receive the threaded studs 17, which hold the demountable and collapsible cap 18 in position at the end of the case. The cap is preferably made of a flexible material such as semisoft leather or canvas and is mounted on a frame comprising two side bars 19 and 20 pivotally connected at 60 their ends by the hinged joints 21 and the hinge bars 22. Each hinge bar is formed in two pieces connected by the pivotal joint 23 so that the frame formed by these elements may be collapsed by the inward 65 movement of the hinge bars to enable it to be folded when not in use. The pivot pins 25 in each hinge joint 21 are offset and terminate in the threaded stud 17. Wing nuts 24 are provided to secure the studs 70 17 in the apertures 16 and as the wing nuts are on the inside of the case, the cap cannot be removed without opening the case. This feature will be found particularly effective 75 in preventing the theft of clubs.

Packing chambers 26 extending the length of the case between the ends 13 and 14 are provided on opposite sides of the I-shaped central portion. These chambers are large 80 enough to hold clothing and are closed by suitable covers 27 secured by hinges 28 along the bottom of the case. The covers 27 are preferably provided with a flange 29 which seats in a rabbet 31 in the top of the overhanging base 11. Suitable fastening means 85 32 of conventional form are provided for locking the cover in closed position.

Means are provided on the top of the case for carrying it over the shoulder or by the hand. When not being used in the capacity 90 of a golf bag, the case may be carried by the handle 33, and for use on the golf links the strap 34 is provided. This strap is preferably detachable at one end and is mounted at the other end to permit the optional 100 positioning of the strap within the case when not in use.

I claim:

1. A golf club carrying case comprising an end opening central portion for the reception of golf clubs, a cap adapted to cover the ends of the projecting clubs, means operable only from within the case for demountably securing the cap on said case, 105 packing chambers on opposite sides of said central portion, and hinged covers for closing said packing chambers.

2. A golf club carrying case comprising an end opening central portion for the reception of golf clubs, a flexible collapsible cap adapted to cover the ends of the projecting golf clubs, means operable from within the case for demountably securing the cap on said case, packing chambers on opposite sides of said central portion, and hinged covers for closing said packing chambers.
3. A golf club carrying case comprising a rigid structure provided with an end forming central portion having individual compartments for the reception of each club, rigid box-like packing chambers on opposite sides of said central portion, and rigid covers hinged parallel to the longitudinal axis of said case for closing said chambers.
4. A golf club carrying case comprising an end opening central portion having individual compartments for the reception of each club, a demountable cap adapted to cover the ends of the projecting clubs, means operable only from within the case for secur-

ing the cap on said case, packing chambers 25 on opposite sides of said central portion, and covers hinged parallel to the longitudinal axis of said case for closing said chambers.

5. A golf club carrying case comprising an end opening central portion for the reception of golf clubs, packing chambers on opposite sides of said central portion, hinged covers for closing said packing chambers, a strap for carrying said case, and a mounting 20 for one end of the strap to permit the optional positioning of the strap within or without the case.

6. A carrying case having an end from which articles in the case project, a demountable cap comprising a collapsible frame, a 40 covering on said frame, studs projecting from said frame and adapted to engage the end of the case, and means operable from within the case for locking said studs in position.

In testimony whereof, I have hereunto set 45 my hand.

HAROLD A. SAMPSON.
